UNITED STATES PATENT OFFICE.

HENRY W. BUHLER, OF BOSTON, MASSACHUSETTS.

COKE-OVEN.

1,341,258.

Specification of Letters Patent.

Patented May 25, 1920.

Application filed February 23, 1917. Serial No. 150,579.

To all whom it may concern:

Be it known that I, HENRY W. BUHLER, a citizen of the United States of America, residing at Boston, county of Suffolk, State of Massachusetts, have invented certain new and useful Improvements in Coke-Ovens, of which the following is a specification.

My invention relates to the utilization of highly combustible, or quickly burning fuels, such as coal gas, in situations where it is desirable to extend the area of combustion beyond the zone or limits in which it would normally occur if a jet of pure gas were employed with ordinary air, preheated or not, as a supporter of such combustion.

In the practice and use of industrial furnaces, it is frequently necessary to secure a long, even flame of combustion. This is particularly true of coke ovens which are constantly increasing in size and of which the combustion chambers must be correspondingly lengthened or heightened. In the use of coal gas, the combustion does not normally take place at a uniform rate, but is usually most intensive near the burners, or, in other words, the first point of contact of the gas and air. From the initial point of combustion, the intensity of combustion falls off more or less rapidly according to the character of the burners and the method of combining the combustible and oxidizing agent.

The particular object of this invention is to secure in a coke oven of any type having either horizontal or vertical flues, with or without regeneration or recuperation, means for producing a long, smooth flame which will give such a distribution of heat throughout the length of the heating flues as may be desired. In some types of coke ovens, it may be necessary to have the most intense combustion near the burner, and in others, at the point farthest removed from the burners. The process constituting the principal feature of my present invention permits the regulation of the flame so that at will its character may be changed to suit the conditions and design of the coking structure or other heating apparatus employed. By my invention this result is accomplished by suitably diluting the highly combustible gas at the nozzle of the burner or before the nozzle is reached, with a practically inert gas whereby the rapidity of combustion is delayed. While my invention may be put into operation with many different forms of

apparatus, two of the best forms of such apparatus at present known to me are illustrated in the accompanying drawings in which—

Figure 1 is a section on the line A—B of Fig. 2, and G—H of Fig. 4, and shows a vertical section through the gas burners and flues alternately used for air and gas or for waste gas.

Fig. 2 is a vertical section on the line K—L of Fig. 1 and C—D of Fig. 4, looking to the left, the section plane passing through a heating flue to which gas and air are being supplied.

Fig. 3 is a vertical section on the line M—N of Fig. 1 and E—F of Fig. 4, looking to the left, the section plane passing through a heating flue from which waste gas is being discharged.

Fig. 4 is a horizontal section on the line I—J of Fig. 1, looking downward, and shows the staggering of the air and gas connections in the base of the heating flues, the dotted arrows indicating the direction of flow of the materials for, and products of, combustion.

Figs. 1 to 4 illustrate the application of my invention to a coking apparatus of the type shown in my pending application Serial No. 144,961, filed Jan. 27, 1917.

Fig. 5 is a vertical section through Fig. 6 on the line A—B, looking to the right.

Fig. 6 is a partial end view or elevation of Fig. 5, and (so far as the portion to the left of line X—Y is concerned) a vertical section on line R—S of Fig. 5. These figures of drawing illustrate the application of my invention to a coking apparatus of the type shown in my U. S. Patent No. 1,314,841, dated Oct. 28, 1919.

Throughout the drawings like reference characters indicate like parts.

Referring to Figs. 1 to 4, coking chambers 1, are formed by a plurality of walls 2. Bonding walls 5, and 5^a, (connecting walls 2, 2) form a series of vertical heating flues 3 and 4. These flues are connected and operated in pairs, as shown in Fig. 1, and as described in my application Serial No. 144,961. Access to the flues is had through the top 11, of the oven by means of ports 9, closed by covers 10. At the top of each pair of flues is a connecting passage or port 7, formed in extensions 6, of the bonding walls 5^a, the area of which may be varied by adjustment of the movable damper 8.

Gas for combustion may be taken from the storage holder 23, by means of pipe 24, and branch pipes 25 and 25^a, each of which supplies one of two series of burners. Gas main 25, supplies pipes 27, and burners 29, controlled by cocks 28. These burners 29, ultimately discharge into flues 4, 4. Gas main 25^a, through gas cock 28^a, and pipe 27^a, supplies burners 29^a, which ultimately discharge into flues 3, 3. Gas mains 25, and 25^a, each have a regulating valve 26, and 26^a. Burners 29, primarily discharge into mixing chambers 14^m, formed in the outer concentric pipes 14, and burners 29^a, primarily discharge into similar mixing chambers 14^m, in pipes 14^a. A removable nozzle 13, rests on the open end of each outer pipe 14, and a similar nozzle 13^a, on each pipe 14^a. These nozzles and the extensions of pipes 14, 14^a, beyond the ends of burners 29, and 29^a, form the mixing chambers 14^m.

The diluent gas may be conveniently taken from the chimney flue 22, by means of an exhauster 21, which supplies main 20, 25 having two branches 18 and 18^a, controlled by valves 19, 19^a, which supply each one of the two series of pipes 14, 14^a, through regulating cocks 17 and 17^a, and branch pipes 16, 16^a. These pipes 14, 14^a, are inserted in vertical passageways 12, 12^a, in the bottom walls of the flues, communicating with the heating flues 3 and 4. These passageways are closed at their lower ends by covers 15, 15^a. Nozzles 13, 13^a, discharge into the passageways 12, 12^a, at points below the base of the heating flues.

In the arrangement shown in the drawings, Figs. 1 to 4, valve 26, is supposed to be open and gas flowing through burners 29, to flues 4. Air for combustion then enters through sole flue 30, and is delivered to each vertical flue 4, through passageways 31, 32, and bore 33, of flue connection 34, inserted in vertical passageway 35, through the bottom wall of the flue. 34, is held in place by a plug 36, which, together with cap 37, closes the lower portion of passageway 35. Parts marked 30, 31^a, 32^a, 33^a, 34^a, 35^a, 36^a, and 37^a, perform similar functions 50 coöperating with burners 29, when they are supplied with gas through main 25^a, to produce combustion in flues 3, 3, during the other cycle of operation of this reversible apparatus. In these figures showing the materials for combustion being fed up into flues 4, the gases of combustion are shown passing from flues 4, through ports 7, into and down through flues 3, so that passages 33^a, 32^a, 31^a, serve as an outlet for the burnt 55 gases to collecting flue 30^a, and no gas is supplied to burners 29^a, valve 26^a, being closed.

The operation of this apparatus according to my method is as follows:

65 Combustion takes place in the heating

flues 4, and the waste products pass down and out of heating flues 3. From the gas holder 23, through mains 24, and 25, branch pipes 27, and burners 29, gas is admitted to the upper part or mixing chamber 14^m, of 70 each pipe 14. The amount of gas admitted to pipe 25, which supplies the gas for one oven may be regulated by cock 26, and the amount of gas admitted to each burner may be regulated by the branch cocks 28. From 75 the chimney flue 22, or any other convenient source by means of the exhauster 21, diluent main 20, and branch main 18, the diluent waste gas which is practically incom- 80 bustible is admitted to each mixing chamber 14^m, through branch pipes 16, controlled by cock 17, and vertical pipe 14.

In the mixing chambers 14^m, the combustible gas and diluent gas are thoroughly mixed, the stream of combustible gas being 85 forced into the body of diluent gas in mixing chambers 14^m, and the mixture so formed, and rising through the nozzle 13, and passageway 12, is discharged into heating flue 4.

Preheated air for combustion enters through the sole flue 30, passageways 31, 32, and bore 33, of flue connection 34, and, coming in contact with the diluted combustible gas, combustion begins in the heating 90 flue 4, continues up that flue, through connecting passageways or ports 7, and down heating flue 3, the waste products of combustion being discharged into bore 33^a, of flue connection 34^a and through passageways 32^a and 31^a, into sole flue 30^a, which is serving as a collecting flue for the two sets 100 of combustion flues on either side the oven 1, above it.

Upon reversal, the directions of flow of 105 all materials and products of combustion are reversed in the manner usual in reversible regenerative ovens, all as set forth in my pending application Serial No. 144,961.

While ordinarily the diluent waste gas is 110 supplied only to the set of burners in operation, it may become advisable to inject diluent waste gas into all burners continuously, so that during the period of "off gas" all the mixing chambers 14^m, nozzles 13 and 13^a, and passages 12, and 12^a, may be scavenged. In such case the diluent gas supplied to the flues from which burnt gases are being discharged will simply pass over directly to the waste gas outlets as indicated by curved arrows in Fig. 3. This will also serve to reduce the temperature of the outlet passages if the waste gases are overheating them.

It will be seen that by this arrangement 115 it is possible to regulate at will the amounts each of combustible gas, diluent inert gas and air for combustion (the latter by variable sized flue connections serving as air-nozzles 34, and 34^a) so that the character 130

and rate of combustion and amplitude of flame in the heating flues may be varied as desired. All the nozzles, tubes, valves, etc., of the combustible gas, diluent inert gas, and air supply connection may be easily removed and inspected and burnt-out pieces replaced.

By making the flues 3 and 4, of elongated cross section and placing the fuel inlets 10 near one end and the air inlet near the other end of each flue cross section, as shown in Fig. 4, it is possible to separate these inlets by a considerable distance and this also tends to delay or prolong combustion, 15 thus extending the zone of combustion farther up the flue and disseminating the heat more widely.

In Figs. 5 and 6 are shown similar coking chambers 41, 41, which are, however, 20 heated by a series of superimposed horizontal heating flues 42, formed by walls 43, and 44. These heating flues 42, communicate with a vertical flue 49, through restricted ports 48, formed in end walls 45. 25 The area of the cross section of the ports 48, may be varied by movable dampers 46, held in place by projections 47, and operated through the passageway 51, in the top wall or roof 53. Passageway 51, is 30 normally closed by dampers 50, and 52. The products of combustion pass down flue 49, are discharged through an outlet dampered by tile 54, all as described in my pending application Serial No. 144,170.

35 Diluent gas is supplied to the heating flues 42, from the mains 55, through branch pipes 56, regulated by cocks 57, and nozzles 58, into mixing chamber 59^m. This diluent gas may be taken as before from a chimney flue by a fan not shown. Combustible gas 40 is supplied by main 60, from which it is distributed to each of the heating flues by branch pipes 61, controlled by cocks 62, and burners 59. Mixing chambers 59^m, 45 charge into refractory nozzles 63, having orifices 64.

Air for combustion is supplied to each flue from a vertical air channel 65, by means of ports 67, controlled by dampers 66. This 50 air may or may not be pre-heated, as desired.

The process as applied to such a coke oven with horizontal heating flues shown in Figs. 5 and 6, and above described briefly, is 55 the same as that previously described with regard to its use with reversible regenerative ovens, except that in this example the flow of gas is positive, continuous and not reversible, and a jet or stream of diluent 60 gas is discharged into a concentric body of combustible gas in each mixing chamber 59^m, instead of the reverse arrangement described with reference to chamber 14^m.

Combustible gas from the main 60, in 65 regulated amounts is delivered into the mix-

ing chambers 59^m. Diluent inert gas supplied from main 55, in regulated quantity is also delivered into the mixing chambers 59^m. This becoming thoroughly intermingled with the combustible gas, the mixture 70 is discharged through orifices 64, of nozzles 63, into the heating flues 42, where it meets the air for combustion delivered through ports 67, and combustion takes place along the entire length of the heating flues 42. The products of combustion 75 pass out through the dampered ports 48, and down the vertical flue 49. As in the previous case described with reference to Figs. 1 to 4, the quantities of diluent inert 80 gas and air supplied to each burner may be regulated at will so that the rate, character and amplitude of combustion may be controlled throughout the length of the heating flues.

85 The great advantage of my process lies in the complete control of the character and location of combustion which it gives without adding to the work thrown upon the regenerators or recuperators. The amount of 90 air required to support combustion of a given amount of fuel designed to produce a given amount of heat in the combustion flues is not increased. Consequently, the standard practice may be followed in designing the 95 regenerators and recuperators, gas mains and burners and all other parts of the plant, and costs kept down to standard figures. All that is necessary is to add the system of piping and the exhauster required to draw a 100 small quantity of waste gas from the chimney flue and deliver it to the burners or fuel mains. The volume of diluent gas required will rarely exceed that of the combustible gas and usually will be less. It will not 105 therefore increase the volume of materials for combustion delivered to the heating flues and the volume of products of combustion, more than 15 per cent over the figures applying where the same quantity of fuel is 110 burned under standard practice. Usually the increase will be much less than 15 per cent, and no increase in size of combustion flues or other passages will be necessary.

The rate or speed of combustion can be, however, cut down about one half and the completion of oxidation of the fuel thereby delayed until the outlet from the flues is reached, or nearly reached, so that all portions of the adjacent retorts are evenly heated 120 by the extended zone of combustion so created. If on the other hand this result were sought to be obtained by diluting the air with an inert gas (instead of diluting the combustible as in my invention) the volume 125 of gases created would be increased nearly 100 per cent and much larger flues and much larger regenerators or recuperators would have to be built, and about five times as large a volume of diluent gas would have to be 130

handled by the fan. In contrast to all this, my invention can be applied to existing coking apparatus without changing the existing structure, only a little extra piping and a small fan or exhaust being required in addition to the old plant.

I wish it understood that various changes can be made in the details of construction here shown and described without departing from the substance of my invention so long as the general principles of operation and coaction of parts herein set forth are preserved.

Having described my invention, I claim:

- 15 1. In a heating apparatus the combination of a central vertical burner tube open at the top, a source of combustible gas, means connecting the burner at its bottom to said source of combustible gas, an outer concentric burner having its upper end projecting beyond the inner tube, a source of practically inert diluent gas, and means connecting the lower end of said outer tube to said source of diluent gas.
- 20 2. In a heating apparatus the combination of a central vertical burner tube open at the top, a source of combustible gas, means connecting the burner tube at its bottom to said source of combustible gas, an outer concentric burner tube having its upper end pro-
- 25 3. In a heating apparatus the combination of a central vertical burner tube open at the top, a source of combustible gas, means connecting the burner tube at its bottom to said source of combustible gas, an outer concentric burner tube having its upper end projecting beyond the inner tube, a source of practically inert diluent gas, and means connecting the lower end of said outer tube to said source of diluent gas, together with a nozzle of refractory material mounted in the upper end of the outer tube.
- 30 4. In a heating apparatus the combination of a central vertical burner tube open at the top, a source of combustible gas, means connecting the burner tube at its bottom to said source of combustible gas, an outer concentric burner tube having its upper end projecting beyond the inner tube, a source of practically inert diluent gas, and means connecting the lower end of said outer tube to said source of diluent gas, together with a removable nozzle of refractory material mounted in the upper end of the outer tube.

jecting beyond the inner tube, a source of practically inert diluent gas, and means connecting the lower end of said outer tube to said source of diluent gas, together with a valve in each connecting means.

35 3. In a heating apparatus the combination of a central vertical burner tube open at the top, a source of combustible gas, means connecting the burner tube at its bottom to said source of combustible gas, an outer concentric burner tube having its upper end projecting beyond the inner tube, a source of practically inert diluent gas, and means connecting the lower end of said outer tube to said source of diluent gas, together with a nozzle of refractory material mounted in the upper end of the outer tube.

40 4. In a heating apparatus the combination of a central vertical burner tube open at the top, a source of combustible gas, means connecting the burner tube at its bottom to said source of combustible gas, an outer concentric burner tube having its upper end projecting beyond the inner tube, a source of practically inert diluent gas, and means connecting the lower end of said outer tube to said source of diluent gas, together with a removable nozzle of refractory material mounted in the upper end of the outer tube.

45 50 55 HENRY W. BUHLER.
